UNITED STATES PATENT OFFICE.

JOHN S. TOLLEFSON, OF BRAINERD, MINNESOTA.

WATER-FILTER.

No. 864,345.

Specification of Letters Patent.

Patented Aug. 27, 1907.

Application filed November 12, 1906. Serial No. 343,097.

To all whom it may concern:

Be it known that I, JOHN S. TOLLEFSON, a citizen of the United States, residing at Brainerd, in the county of Crow Wing and State of Minnesota, have invented 5 a new and useful Water-Filter, of which the following is a specification.

This invention relates to a filter for liquids and is designed more particularly for use as a water tender screen cup for supplying filtered water from the tender 10 of a locomotive to the boiler, and while the invention is particularly suited to this use, it possesses certain features whereby drinking water, or other liquids, can be freed from sediment, germs, and other foreign matter.

15 The invention has for one of its objects to improve and simplify the construction and operation of devices of this character, so as to comprise few parts which are easy and inexpensive to construct and readily assembled and taken apart so as to be kept 20 clean or repaired with great facility.

A further object of the invention is to provide a filter in which water can be quickly filtered or screened, and the sediment and foreign matter readily drawn off from the collecting chamber or well of the filter.

25 With these objects in view, and others, as will appear as the nature of the invention is better understood, the invention comprises the various novel features of construction and arrangement of parts, which will be more fully described hereinafter, and set forth 30 with particularity in the claims appended hereto.

In the accompanying drawing, which illustrates one of the embodiments of the invention, Figure 1 is a longitudinal sectional view of the filter. Fig. 2 is a transverse sectional view of the filter taken at the 35 outlet pipes.

Corresponding parts in the several figures are indicated throughout by similar characters of reference.

Referring to the drawing, 1 designates the cylindrical body of the filter or screen cup, 2 the bell-shaped cover or cap, and 3 the cup-shaped bottom or well. These parts are preferably castings and made 40 of the same diameter and are arranged on a common axis end to end.

The adjacent ends of the several sections are provided with transversely extending peripheral flanges 4 which are carefully finished or ground so that the cap and collecting well make a fluid tight fit with the body 1. The flanges 4 are apertured for receiving the bolts 5 whereby the cap 2 and collecting well 3 are 45 securely held on the body 1. While this construction is preferable, I do not desire to be limited thereto, since the casing of the filter can be made in any other suitable manner.

50 The casing is provided with an inlet 6 at the center of the cap 2, and into this inlet is threaded a supply pipe 7.

One or more outlets are provided in the wall of the casing for the filtered water, as, for instance, the outlets 8 and 9 located preferably in the body portion 1 of the casing. Bosses 10 are formed at these openings 60 and the outlet pipes 11 and 12 are threaded in the same. The pipe 11 serves to supply the filtered water to any point of consumption, as, for instance, the boiler of a locomotive, and the said pipe is provided with a cut-off valve 13. The other pipe 12 is fitted 65 with a faucet 14 whereby filtered water can be drawn off into a bucket or other receptacle for any desired purpose.

The filtering element in the casing may be of any desired construction, depending largely upon the liquid 70 to be filtered and the degree of filtration desired. The filtering element shown in the present instance is intended to strain water supplied from the tender of a locomotive to the boiler, and for this purpose comprises a section of perforated pipe 15, the perforations 75 16 of which are of any desired size and arrangement. The tube or pipe 15 is arranged concentrically within the casing and is supported therein by a socket 17 cast integral with the upper end of the well 3. The socket 17 is supported by means of spaced webs 18, segmental 80 openings 18' being provided around the socket so as to permit sediment and other matter to freely collect in the well 3 from the upper part of the filter casing. The socket 17 is interiorly threaded and the lower end of the pipe 15 is screwed into the same, the bottom 19 85 of the socket serving as a head or cap for the said pipe. The upper end of the filter pipe 15 is provided with a cap 19' that is removably held thereon, as by means of screw threads. Covering the perforations 16 is a straining device 20, such as a wire gauze of extremely 90 fine mesh. This gauze is formed into the shape of a cylinder and is fitted over the pipe 14 with its ends soldered to the latter, if desired. The outlet pipes 11 and 12 are screwed into the casing a sufficient distance to project beyond the internal wall of the body 1, and 95 on these inwardly projecting ends 21 of the outlet pipes are tubular gaskets 22, preferably of rubber or equivalent material. These gaskets are held firmly in place by engagement with the threads on the outlet pipes. The inner ends of the gaskets are shaped to 100 conform to the curvature of the filtering element, and they are so adjusted on the outlet pipes that when the filtering element is assembled, the gaskets will fit tightly against the latter. The tube 15 is provided with an outlet opening 23 at each pipe 11 and 12. In 105 assembling the parts, the openings 23 are caused to align with their respective pipes 11 and 12 by means of a pin 24 on the flange 4 of the well 3 engaging in an opening provided in the bottom flange 4 of the body 1.

In operation, the liquid to be filtered is supplied 110 to the casing of the filter or screen cup, and the water fills the space between the filtering element and the

casing. This water is prevented from passing directly to the outlet pipes by means of the gaskets 22, and in order to pass to the outlet pipes, the water or other liquid percolates through the filtering element to the interior thereof and then flows outwardly through the outlet portions inclosed by the gaskets 22 and thence into the outlet pipes. It will thus be seen that the water is twice filtered, that is to say, it is filtered in passing into the filtering element and again in passing out of the same to the outlet pipes. The sediment and other material separated by the screen 20 is collected in the well 3 and, whenever it is desired to clean the latter, the drain pipe 25, which is provided with a valve, (not shown) is opened and the interior of the filter, including the screen 20, can be thoroughly flushed by maintaining the supply of water to the filter through the pipe 7 while the drain opening 25 is open. When it is desired to clean out the interior of the filtering element, the well 3 can be taken off with the filtering element attached thereto. The cap 19' of the filtering element is then unscrewed and the interior exposed for the purpose of cleansing in any suitable manner; as, for instance, by directing a jet of steam from a steam hose or pipe, so as to clean out the interior quickly and thoroughly.

What is claimed is:—

1. A filter comprising a casing having an inlet and an outlet, a hollow filtering element having closed ends and arranged in the casing and through which liquid filters first inwardly in a radial direction and then outwardly in a radial direction, a pipe connected to the outlet, and a gasket on the pipe and bearing against the element.
2. A filter comprising a casing, a hollow filtering element therein into which liquid enters by filtering through a portion of its wall and out of which the liquid passes by filtering through another portion, and a conduit arranged at one end in contact and covering one of the said portions.
3. A filter comprising a casing, a hollow filtering element having a pervious body, means for supporting the element in the casing with water space around the element, a pipe communicating with the said space, a second pipe extending through the wall of the casing with its inner end adjacent the filtering element, and a device between the inner end of the said pipe and the filtering element which forms a seal between the second pipe and the said water space.
4. A filter comprising a casing, a tubular filtering element, caps closing both ends thereof, an inlet pipe arranged to supply liquid to the space around the element, a radially extending outlet pipe arranged to receive filtered liquid from the element at a point intermediate the ends of the latter, and a gasket secured on the outlet pipe and bearing against the exterior of the element.

5. A filter comprising a casing, a hollow body mounted in the same and provided with a pervious portion through which liquid enters the body and another pervious portion through which the liquid passes out of the body, a supply pipe discharging into the casing, an outlet pipe passing through the wall of the casing, and a gasket between the outlet pipe and the last mentioned pervious portion of the said body.

6. A filter comprising a casing, a tubular filtering element mounted therein and surrounded by a space, a pipe for supplying liquid to the said space, a plurality of outlet pipes passing into the casing, and gaskets arranged between the said outlet pipes and the filtering element.

7. A filter comprising a casing composed of connected sections arranged end to end, a socket provided on one of the sections, a filtering element removably mounted in the socket and removable with the said section, a pipe communicating with the casing, a second pipe communicating with the interior of the filtering element, and a gasket on the end of the second pipe and bearing upon the exterior of the filtering element without mechanical connection therewith.

8. A filter comprising a body section, a bottom well section, a cap on the body section, means for detachably connecting the sections, a socket on the well section, a perforated tube mounted in the socket, a screen around the tube, a cap on the end of the tube opposite from that in the socket, a pipe communicating with the casing, a second pipe extending into the casing, and a gasket on the second pipe impinging upon the exterior of the screen.

9. A filter comprising a body section, a bottom well section, a cap section, means for detachably connecting the sections, a filtering element supported solely by the well section and extending through the body section and into the cap section, an inlet pipe attached to the cap section, a drainage means on the well section, a pipe extending into the body section, and a device forming a seal between the last mentioned pipe and the filtering element.

10. A filter comprising a body section, a bottom well section, a cap section, flanges on the said sections, bolts extending through the flanges for securing the sections together, a threaded socket provided on the well section, a tube threaded in the socket and provided with a perforated portion, a screening medium over the perforations of the tube, a pipe for supplying liquid to the exterior of the tube for permitting it to filter into the latter, a drainage device at the bottom of the well section, a pipe extending through one of the sections and terminating in proximity to said tube, threads on the inner end of the pipe, and a cylindrical gasket engaging the said threads and having its inner end to conform to the curvature of the tube for bearing against the same and forming a seal.

In testimony that I claim the foregoing as my own, I have hereto affixed my signature in the presence of two witnesses.

JOHN S. TOLLEFSON.
